UNITED STATES PATENT OFFICE

173,246

PORABLE POWER UNIT

James R. West, New Holland, Pa., assignor to The
Sperry Corporation, New Holland, Pa., a cor-
poration of Delaware

Application February 2, 1953, Serial No. 23,400

Term of patent 7 years

(Cl. D26—1)

To all whom it may concern:

Be it known that I, James R. West, have in-
vented a new, original, and ornamental Design
for a Portable Power Unit, of which the follow-
ing is a specification, reference being had to the
accompanying drawing, forming a part thereof.

Figure 1 is a side elevation of a portable power
unit showing my new design.

Figure 2 is a plan view thereof.

Figure 3 is an end elevation thereof.

I claim:

The ornamental design for a portable power
unit, as shown.
